PROTECTIVE RELAY SYSTEM

Roy M. Smith, North Arlington, N. J., assignor to
Westinghouse Electric & Manufacturing Com-
pany, a corporation of Pennsylvania

Application March 18, 1932, Serial No. 599,697

8 Claims. (Cl. 175—294)

My invention relates to relays and has particular relation to relays in which a potential coil is employed. While not limited thereto, my invention is particularly applicable to protective relays for use in operating circuit breakers in response to predetermined electrical conditions occurring in an alternating-current system.

It is an object of my invention to provide a relay which is responsive to predetermined voltage and current conditions, or to predetermined power conditions, in an alternating-current circuit and in which the sensitiveness of the relay is automatically increased when the voltage of such circuit falls below a predetermined value.

Another object of my invention is to provide a relay in which the entire potential coil is effectively energized during normal voltage conditions in an alternating-current circuit but in which a part only of the potential coil is rendered effective when the voltage of the circuit falls below a predetermined value.

Another object of the present invention is to provide a protective relay of the induction type having means incorporated therein for rendering the relay inversely sensitive to the energization thereof.

Other objects of my invention will become evident from the following detailed description taken in conjunction with the accompanying drawing, in which

Figure 1 is a schematic illustration in front elevation of a protective relay embodying my invention.

Fig. 2 is a side view of the relay shown in Fig. 1, and

Fig. 3 is a diagrammatic view of a protective system utilizing my invention.

Referring to Figs. 1 and 2 of the drawing, an induction-disc type relay is illustrated as comprising a magnetic core 1 having two depending pole portions upon which are mounted current coils 2 and 3, and having a third or main pole portion upon which is mounted a voltage coil 4.

A non-magnetic disc 12, secured to a rotatable shaft or spindle 13, is positioned for rotation in the air gap between the cores of the current and potential coils 2, 3 and 4, respectively, in a usual manner. The current coils 2 and 3 are connected in series and, when energized, cooperate with the energized voltage coil 4 to produce a rotating torque acting on the disc armature 12. The magnitude and direction of the torque is determined by the resultant fluxes produced by the energized coils 2, 3 and 4 acting on the disc armature 12.

A moving contact 14 is secured to the spindle 13 and is arranged to bridge a pair of stationary contact members 15 when the disc is rotated in one direction. A stop 17 is mounted in a position to be engaged by the arm 14 to limit the rotation of the disc and spindle in the opposite direction.

A magnetic vane armature 5 is pivoted, at one end, to a bracket 6 secured to one side of the core 1. The free end of the armature 5 is positioned to engage a contact member 7, secured to the core 1, or a contact member 8, affixed to a bracket 9. The bracket 9 is secured to the core 1, in any suitable manner, by means of a screw 10 or other securing means. A coil spring 11 is provided for biasing the armature 5 to the position in which it engages the contact member 8.

Under normal conditions, when the potential coil 4 is fully energized, the armature 5 is held in engagement with the contact member 7 against the bias of the spring 11, by the magnetic flux in the main pole of core member 1. When the voltage applied to the potential coil 4 falls below a predetermined value, the decreased magnetic flux produced by the coil in the main pole is insufficient to maintain the armature 5 in engagement with the contact member 7. The spring 11 then causes the armature 5 to rotate about its pivot into engagement with the contact member 8.

The contact member 7 is connected to one terminal of the potential coil 4, by means of a conductor 18, so that voltage is applied to the entire potential coil when the armature 5 is in engagement with this contact member. The contact member 8 is connected to an intermediate tap 90 on the potential coil 4, by means of a conductor 19. With such arrangement, only a portion of the potential coil has voltage applied thereto when the armature is in engagement with the terminal 8.

The magnitude and direction of torque acting on the disc 12 depends upon the magnitude and direction of power flowing in the alternating current circuit to which the relay is adapted to be connected. A decrease of voltage of the circuit 100 necessitates a correspondingly higher value of current in the circuit to operate the relay. However, if the voltage decreases below the predetermined value at which the armature 5 is designed to release, the armature disengages the contact member 7 and moves into engagement with the contact member 8, thereby establishing a voltage connection through part only of the turns of potential coil 4. Because of the greatly reduced impedance of the circuit including the potential coil 110

4, the flux produced by the latter coil increases, thereby reducing the value of current necessary to operate the relay.

Referring more particularly to Fig. 3, I have illustrated one application of my invention for the protection of a power circuit. Conductors L1 and L2 represent a suitable power circuit to which are connected the primary windings of a current transformer 20 and a potential transformer 21. 10 The current coils 2 and 3 of the relay are connected to the secondary winding of the current transformer 20 by means of conductors 22 and 23 and the potential coil 4 is connected to the secondary winding of the potential transformer 21, 15 by means of conductors 24 and 25. The conductor 24, however, is connected to the armature 5 and is adapted to engage the contact members 7 or 8, depending on the voltage applied to the potential coil 4.

20 The stationary contact members 15 are connected in a circuit which includes a suitable source of energy, such as a battery 26, and a trip coil 27 of a circuit breaker 31 for opening the power circuit. For simplicity I have illustrated a 25 circuit breaker of the manually reclosed type; however it will be understood that my invention may be practiced with any usual type of manually or automatically reclosed breaker and, of course, may be practiced in more elaborate protective systems than the one illustrated.

The operation of the scheme shown in Fig. 3 is as follows: Assuming the circuit breaker to be closed and that power is flowing in the proper direction through conductors L1 and L2, a current 35 proportional to the main current flows through the current coils 2 and 3, and a voltage proportional to the main voltage is impressed upon the entire potential coil 4. The magnetic flux produced by the potential coil 4 maintains the armature 5 in engagement with the contact member 7 as long as the voltage between the main conductors L1 and L2 remains normal. The rotating field produced jointly by the current and potential coils rotates the disc 12 and spindle 13 in 40 the usual manner until the moving contact 14 strikes the stop 17. The relay then remains in this position as long as normal conditions exist in the power circuit.

Assuming, however, that some abnormal condition occurs in the power circuit which causes the voltage applied to the potential coil 4, to fall 50 below the predetermined value at which the armature 5 is designed to operate, then the magnetic flux produced by the potential coil decreases, so that the spring 11 causes the armature 5 to rotate about its pivot into engagement with the contact member 8.

This reduces the impedance of the circuit including the potential coil 4, in the manner previously described, and causes the flux produced by the latter coil to increase. If now the direction of power flow in the main conductors L1 and L2 reverses, the direction of torque applied to the disc 12 reverses, and the moving contact 14 60 moves into engagement with the contact members 15. Because of the increased flux produced by coil 4, a minimum of reverse current is required for the performance of the latter operation. Upon the engagement of the moving contact 14 with the stationary contacts 15, a circuit 65 is completed for the trip coil 27 of the circuit breaker. The circuit breaker 31 is thereupon actuated to its open position and the circuit breaker may be manually reclosed in the usual 70

manner when the fault or abnormal power condition on conductors L1 and L2 is remedied.

It is, therefore, apparent to those skilled in the art that I have provided a relay that is sensitive to predetermined voltage and current, or to predetermined power conditions, and in which the sensitiveness of the relay is automatically increased when the voltage of the power system falls below a predetermined definite value. The relay is, furthermore, sensitively responsive to reversal 85 of power with moderate values of reverse current in the power circuit under a wide range of values of line voltage.

Although I have shown one specific embodiment of my invention I do not desire to be limited there- 90 to as various other modifications may be made without departing from the spirit and scope of the appended claims.

I claim as my invention:

1. In protective apparatus for an electric circuit, a circuit breaker for controlling said circuit, control means for said circuit breaker including a relay having coil means, energizing means for said relay including electrical connections for normally energizing a predetermined number of 100 turns of said coil means in accordance with an electrical condition of said circuit, and means responsive to a predetermined reduction of voltage in said circuit for modifying said connections to cause a different predetermined number of turns 105 of said coil means to be energized in accordance with said electrical condition, to thereby alter the sensitiveness of said relay under low voltage conditions of said circuit.

2. In protective apparatus for an electric circuit, a circuit breaker for controlling said circuit, control means for said circuit breaker including a relay having a magnetic core, a coil in inductive relationship to said core and a main armature responsive to a magnetic condition of said core, 110 energizing means for said relay including electrical connections between said circuit and said coil for normally maintaining a predetermined ratio between an electrical condition of said circuit and a magnetomotive force applied to said core, and 115 means including an auxiliary armature responsive to a predetermined abnormal flux condition of said core for modifying said connections to establish a different predetermined ratio between said electrical condition of said circuit and said mag- 120 netomotive force.

3. In a protective system, an electrical circuit, a circuit breaker for interrupting said circuit, means for actuating said circuit breaker upon the occurrence of predetermined electrical 130 conditions in said circuit including a relay having a potential coil and a potential circuit for applying a voltage to said coil, and means associated with said coil responsive to a predetermined decrease of voltage of said circuit for excluding the 135 entire potential coil from said potential circuit and inserting a portion only of said coil in said potential circuit to increase the sensitiveness of said relay.

4. In a relay, a magnetic structure having a plurality of spaced pole members defining an air gap, a plurality of coils mounted upon said pole members, a disc armature pivotally mounted for rotation in said air gap, contact members controlled by said disc armature, energizing connections for said coils including a circuit of predetermined impedance phase angle for energizing one of said coils, an auxiliary armature mounted to move in response to variations of flux in one of said pole members, auxiliary contact members controlled by 140 145 150

5. In protective apparatus for an alternating current circuit, a circuit breaker for controlling said circuit, control means for said circuit breaker including a relay having a magnetic core, a first coil in inductive relationship to said core, a second coil and an element responsive to a vector product of magnetic conditions produced by said coils, energizing means for said relay including electrical connections for normally maintaining a predetermined ratio and a predetermined phase relationship between an electrical condition of said circuit and a magnetic condition produced by said first coil, and means responsive to a predetermined abnormal flux condition of said core 10 for modifying said connections to establish a different predetermined ratio and to maintain substantially the same predetermined phase relationship between said electrical condition and said magnetic condition, to thereby alter the sensitivity but not the phase angle characteristics of said relay during an abnormal condition of said circuit.

6. In a relay, a magnetic structure having a plurality of spaced pole members defining an air gap, current coils and a potential coil mounted upon said pole members, a disc armature pivotally mounted for rotation in said air gap, contact members controlled by said disc armature, an auxiliary armature mounted to move in response to variations of voltage impressed upon said potential coil, and means including contact members controlled by said auxiliary armature for causing a predetermined voltage to be impressed upon the entire potential coil or a portion only of said coil depending upon the variation of the impressed voltage.

7. In a relay, a magnetic structure having a plurality of spaced pole members defining an air gap, current coils and a potential coil mounted upon said pole members for operating said relay when current and voltage are applied to the respective coils, a disc armature pivotally mounted for rotation in said air gap, contact members controlled by said disc armature, an auxiliary armature mounted to move in response to variations of flux produced by said potential coil, and means including contact members controlled by said auxiliary armature for causing said voltage to be impressed upon the entire potential coil when said voltage is above a predetermined value, or to be applied to a portion only of said coil when said voltage is below a predetermined value, to thereby reduce the value of current necessary to operate said relay during an undervoltage condition.

8. In a protective system, an electrical circuit, a circuit breaker for interrupting said circuit, means for actuating said circuit breaker upon the occurrence of a predetermined electrical condition in said circuit including a relay comprising a magnetic structure having a plurality of spaced pole members defining an air gap, current coils and a potential coil mounted upon said pole members, a disc armature pivotally mounted for rotation in said air gap, contact members controlled by said disc armature, a magnetic armature mounted to move in response to variations of voltage impressed upon said potential coil, and means including contact members controlled by said magnetic armature for causing a predetermined voltage to be impressed upon the entire potential coil or a portion only of said coil to increase the sensitiveness of said relay.
